RHEOSTAT CONTROL

John H. Brownfield, United States Navy

Application November 17, 1939, Serial No. 304,967

3 Claims. (Cl. 200—50)

(Granted under the act of March 3, 1883, as
amended April 30, 1928; 370 O. G. 757)

This invention relates to a rheostat control or current regulator for electrical devices such as motors or the like, wherein it is desirable that the current be fed thereto at a predetermined rate to thus prevent injury to machinery caused by an excess of current before the machinery has picked up its load.

A further object of this invention is to provide a rheostat control or switch for the starting and control of A. C. or D. C. motors which may be operated instantly yet which will interpose a resistance between the source of current and the motor and will cut out the resistance at a rate predetermined according to the particular setting of a valve.

A further object of this invention is to provide a control switch for motors which, although it includes the passage of a quantity of mercury from one container to another container through a valve to progressively cut out resistance according to the rate of flow of the mercury or other electroconductive fluid, yet can be used for marine motor starting applications due to the presence of an additional solenoid operated valve in the interconnecting line which will maintain the mercury level substantially constant in the rheostat mercury container in spite of the roll and pitch of a ship on which it may be located.

With the foregoing and other objects in view, the invention consists in the construction, combination and arrangement of parts hereinafter described and illustrated in the drawings, in which,

Fig. 1 is a schematic view of one form of the invention; and

Fig. 2 is a schematic view of a slightly modified form of the invention.

There is shown at 10 a reservoir properly insulated on the inside and connected by a tubing 11 to a contact cylinder 12. This contact cylinder is fixedly mounted on a supporting wall or surface and is provided with a non-amalgamating copper bus 13 extending vertically on the inside thereof, which has pivoted thereto near its top a copper float 14 adapted to bridge the space therebetween to a copper contact 15 connected by a line 16 to the motor 17 which is to be operated.

The contact cylinder 12 also contains a plurality of vertically spaced contacts 18, each connected through its line 19 and through rheostat resistor elements or auto transformer 20 to the line 16 to lead to the motor. The tops of the reservoir 10 and contact cylinder 12 are interconnected by a tubing 21. The reservoir 10 is

provided with a quantity of electroconductive fluid such as mercury 22 which flows through the tubing 11 to the contact cylinder 12. The reservoir 10 is mounted for vertical movement on a guide 23 and may be raised by means of a handle 24 until the lug 25 contacts and is held by an overload release 26 which is placed in a line 27 between the motor 17 and double pole line switch 28, copper bus 13 also being connected by line 30 to the double pole switch 28.

The current is supplied through the double pole switch by means of the lines 31 leading to the line terminals 32 connected to any suitable source of electrical energy. The tubing 21 and upper portions of the reservoir 10 and contact cylinder 12 may be filled with an inert gas or provided with a vacuum so as to prevent any oxidizing of the electroconductive fluid. The reservoir 10 is provided with a switch operating prong 33 cooperating with the bifurcated fingers 34 and 35 of the double pole switch 28 so as to keep this switch in the "off" position when the reservoir 10 is at the bottom of the guide 23 and to move it to the "on" position when the reservoir 10 is raised vertically to the uppermost position.

As the reservoir 10 is thus raised vertically, the electroconductive fluid in the reservoir 10 commences to flow through the tubing 11 to the contact cylinder 12. This rate of flow may be controlled by means of a gate valve 36, which may be set so as to cause the contact cylinder 12 to be filled up at any desired rate, according to the characteristics of the motor 17 which is to be operated. When the motor is to be cut off the reservoir 10 is merely lowered by means of its handle 24, causing the prong 33 to operate finger 34 and move the double pole switch 28 to the "off" position. Inasmuch as it may be desirable to immediately re-start the motor without waiting for the electroconductive fluid to flow back through the control valve 36 at the same rate as in starting, a by-pass check valve 37 is provided, permitting the fluid to flow back at a rapid rate.

If used on shipboard for marine motors it is desirable to prevent the pitch and roll of the ship from causing the electroconductive fluid level to oscillate. To take care of this a solenoid valve 38 is provided in tubing 11 adapted to remain normally open, except when the current is flowing through an auxiliary contact 42 to the motor 17, being connected thereto by means of the lines 39 and 40. When so used for marine motors the tubing 21 may be filled with any liquid having good dielectric properties in place of the vacuum or the inert gas, and a small expansion chamber

41 of the flexible bellow type is provided to take care of the expansion of the mercury and the dielectric liquid.

In operation, the reservoir 10 is raised along the guide 23 to the topmost position to start the motor, and is lowered to the lowermost position to stop the motor, the valve 36 having first been set to allow the fluid to flow from the reservoir 10 to the contact cylinder 12 at the desired rate according to the characteristics of the motor. The fluid flowing through the tube 11 into the contact cylinder 12 bridges the copper bus 13 to the copper contacts 18 and flows into the contact cylinder 12, progressively cutting out the resistance in the rheostat 20 until it finally reaches the topmost contact 15 and causes the copper float 14 to bridge thereacross, thereby cutting out all of the resistance and allowing the full current to flow to the motor 17. Simultaneously, in a marine installation, the solenoid valve 38 will be closed and prevent any oscillation of the fluid from the reservoir 10 to the contact cylinder 12, and vice versa. The reservoir 10 will be so placed relative to the cylinder 12 that the lowermost contact 18 will always be covered by the electroconductive fluid, and due to the small voltage differences as the resistances in the rheostat 20 are progressively cut out, there will be little or no arcing present.

In the form of the invention shown in Fig. 2, the reference numerals are primed where they correspond in function and are similar in construction to that of the form shown in Fig. 1. In this form the reservoir 10' is mounted on a wheel or spider 50 which also carries a contact cylinder 12'. The wheel or spider 50 is mounted for rotation about a pivot 51 and has a stop 52 limiting its rotation in the "off" direction, while a spring 53 tends to rotate it to such "off" position. To operate the motor 17' the spider 50 is rotated about 20 degrees until it reaches the overload release 26' holding it in such position with the mercury 22' filling the cylinder 12' and causing float 14' to bridge from bus 13' to contact 15'. Otherwise the operation and construction of this form is substantially identical with that of the other form.

Other modifications and changes in the proportions and arrangements of the parts may be made by those skilled in the art without departing from the nature of the invention, within the scope of what is hereinafter claimed.

The invention described herein may be manufactured and/or used by or for the Government of the United States of America for governmental purposes without the payment of any royalty thereon or therefor.

Having thus set forth and disclosed the nature of the invention, what is claimed is:

1. In a current regulator for electrical devices comprising a pair of interconnected receptacles adapted to contain an electroconductive liquid, a vertically extending contact member in one of said receptacles adapted to be connected to one of a pair of lines leading to a source of power,

a plurality of vertically spaced apart contact members in said receptacle spaced from said vertical contact member, a tube means interconnecting said receptacles and means for mounting one of said receptacles for vertical displacement relative to the other of said receptacles whereby the level of the electroconductive liquid may be changed to progressively bridge said vertically spaced contact members to said vertically extending contact member, said mounting means for said one receptacle comprising a vertical guide, a switch in said power lines limiting the movement of said receptacle in one direction and means limiting the movement of said receptacle in the other direction.

2. In a current regulator for electrical devices comprising a pair of interconnected receptacles adapted to contain an electroconductive liquid, a vertically extending contact member in one of said receptacles adapted to be connected to one of a pair of lines leading to a source of power, a plurality of vertically spaced apart contact members in said receptacle spaced from said vertical contact member, a tube means interconnecting said receptacles and means for mounting one of said receptacles for vertical displacement relative to the other of said receptacles whereby the level of the electroconductive liquid may be changed to progressively bridge said vertically spaced contact members to said vertically extending contact member, said mounting means for said one receptacle comprising a wheel on which said receptacle is mounted, a switch in said power lines limiting the rotation of said wheel and receptacle in one direction, and means limiting the rotation of said wheel and receptacle in the other direction.

3. In a current regulator for electrical devices comprising a pair of interconnected receptacles adapted to contain an electroconductive liquid, a vertically extending contact member in one of said receptacles adapted to be connected to one of a pair of lines leading to a source of power, a plurality of vertically spaced apart contact members in said receptacles spaced from said vertical contact member, a tube means interconnecting said receptacles and means for mounting one of said receptacles for vertical displacement relative to the other of said receptacles whereby the level of the electroconductive liquid may be changed to progressively bridge said vertically spaced contact members to said vertically extending contact member, said mounting means for said one receptacle comprising a wheel on which said receptacle is mounted, a switch in said power lines limiting the rotation of said wheel and receptacle in one direction, means limiting the rotation of said wheel and receptacle in the other direction, said limiting means normally holding said wheel against release, and yieldable means urging said wheel to rotate toward said switch when released.

JOHN H. BROWNFIELD.
